CODE DETECTING MEANS

Frank H. Nicholson, Penn Township, Allegheny County, Pa., assignor to The Union Switch & Signal Company, Swissvale, Pa., a corporation of Pennsylvania

Application March 16, 1945, Serial No. 583,058

6 Claims. (Cl. 246—34)

1

My invention relates to coded signaling apparatus and particularly to improved means for detecting coding operation of a code following relay.

An object of my invention is to provide code detecting means which is immune to false response in the event the contacts of the code following relay are defective or out of adjustment.

A further object of this invention is to provide all-relay code detecting means which is arranged so that fused or overlapping contacts on the code following relay cannot result in improper energization of the associated code detecting relays.

Other objects of the invention and features of novelty will be apparent from the following description taken in connection with the accompanying drawing.

I shall describe two forms of code detecting means embodying my invention and shall then point out the novel features thereof in claims.

In practicing my invention, I provide the code following relay with two movable contacts which are operated between a first and a second position substantially in synchronism. These movable contacts are connected by a supply conductor and one contact connects the supply conductor to one or the other terminal of a source according as the contact is in its first or its second position. The other movable contact when in one position establishes connection from the supply conductor through the winding of a first auxiliary or code detecting relay to a terminal of the source, and in its other position establishes connection from said supply conductor through the winding of a second auxiliary or code detecting relay to a terminal of the source providing the contacts of the first auxiliary relay are picked up. The circuits are arranged so that overlapping of the contacts of one of the movable contacts on the code following relay results in short-circuiting of the battery with resultant deenergization of both auxiliary relays, while overlapping of the contacts of the other movable contact on the code following relay results in short circuiting of one or the other of the auxiliary relays.

In the drawing:

Fig. 1 is a diagram of a section of railway track equipped with coded track circuit apparatus and provided with means embodying my invention for detecting code following operation of the track relay, and

Fig. 2 is a diagram showing a modified arrangement adapted for use where code following oper-

2

ation of one or the other of two code following track relays is to be detected.

Similar reference characters refer to similar parts in each of the two views.

5 In most instances in the drawing relay contacts are shown directly under the relay winding, but in some cases in order to simplify the drawing relay contacts are separated from the relay winding and where this is done the relay with which the contact is associated is designated by an appropriate reference character placed directly over the contact.

Referring to Fig. 1 of the accompanying drawing, there is shown therein a section of railway track having track rails 1 and 2 which are separated from the rails of adjacent sections by insulated joints 3. Traffic in this section normally moves in the direction indicated by the arrow, that is, from left to right, and a wayside signal 20 S is located at the entrance end of the section and governs traffic in the section. As shown, the signal S is of the color light type and has a red or stop lamp R and a green or clear lamp G.

A code following track relay TR is connected 25 across the section rails at the entrance end of the section and is operated by master code energy supplied over the section rails from the track battery TB at the exit end of the section. The supply of energy from the track battery to 30 the section rails is controlled by a coding device CT which has a contact 10 which is operated between an open and a closed position at a selected rate, such as 75 to 180 times a minute.

The track relay TR governs the supply of energy to slow release auxiliary relays FSA and BSA from a battery 12, while the relay BSA governs the supply of energy to the lamps of the signal S.

When the track section is vacant, energy supplied from the battery TB during the closed periods of contact 10 of coding device CT feeds over the section rails to the winding of the track relay TR and picks up the contacts of this relay, while during the open periods of contact 40 10 of the coding device CT the supply of energy from battery TB to relay TR is interrupted and the contacts of the relay TR release.

The track relay TR is equipped with a first movable contact 14 and a second movable contact 16 which are connected by a supply conductor 15. The track relay contacts are biased to a released or first position and are movable therefrom to a picked-up or second position.

When the track relay contacts are in their 55 picked-up or second position, energy is supplied

from the second or positive terminal of the battery 12 over front contact 14 of relay TR, supply conductor 15, front contact 16 of relay TR and winding of relay FSA to the first or negative terminal of the battery 12. The energy supplied to relay FSA picks up the relay contact with the result that during the released periods of the track relay TR energy is supplied from the second or positive terminal of the battery through the winding of relay BSA, front contact 17 of relay FSA, back contact 16 of relay TR, wire 15, and back contact 14 of relay TR to the negative or first terminal of the battery 12. Accordingly, contact 18 of relay BSA is picked up and establishes the circuit of the green lamp G of the signal S. The relays FSA and BSA are of a type the contacts of which are slow to release and the contacts of these relays remain picked up during the intervals in which the supply of energy to the relay winding is interrupted.

When a train enters the section, the contacts of relay TR remain released and do not establish the circuit of relay FSA and, after a short time interval, contact 17 of relay FSA releases and interrupts the circuit of relay BSA and its contact 18 releases to interrupt the circuit of the green lamp G and establish the circuit of the red lamp R. When the section is vacated, the track relay again responds to coded energy and energy is supplied to relay FSA during the picked-up periods of the track relay contacts and is supplied to the relay BSA during the released periods of the track relay contacts so that the circuit of the green lamp of signal S is established.

The circuits of the relays FSA and BSA are arranged so that fusing or overlapping of the front and back points of contacts 14 and 16 of the track relay TR cannot result in improper energization of relay BSA with consequent display by the signal S of a green instead of a red indication.

As explained above, when the section is occupied, the contacts of relay TR are released and should interrupt the circuit of relay FSA so that its contact 17 interrupts the circuit of relay BSA and thus causes contact 18 of relay BSA to be released and maintain the circuit of the red lamp of the signal S.

If, for any reason, the movable contact 14 of the track relay TR simultaneously engages its front and back points of contact, a connection will be established between the two terminals of the battery 12 and the battery will be short circuited but energy will not be improperly supplied to relays FSA and BSA and they will remain released and maintain the circuit of the red lamp R of signal S.

If the movable contact 16 of relay TR simultaneously engages its front and back points of contact, and the contact 14 of relay TR engages its front contact, the relay FSA will be energized, but the relay BSA will be shunted over the circuit which is traced from the left-hand terminal of the relay winding over front contact 17 of relay FSA, back contact 16 of relay TR, wire 15, and front contact 14 of relay TR to the right-hand terminal of the winding of relay BSA. As the winding of relay BSA is shunted the relay contact 18 is released and maintains the circuit of the red lamp of the signal S.

Furthermore, under the conditions stated above, the relay BSA not only is shunted, but no circuit is established to supply energy to the relay winding and the relay contact is certain to remain released.

Similarly, if the movable contact 16 of relay TR simultaneously engages its front and back points of contact and contact 14 engages its back contact, the relay FSA will be shunted over the circuit which is traced from the left-hand terminal of the relay winding over front contact 16 of relay TR, wire 15, and back contact 14 of relay TR to the right-hand terminal of the winding of relay FSA. As the winding of relay FSA is short circuited, the relay contact 17 will be released and will interrupt the circuit of relay BSA and thus insure that contact 18 of relay BSA is released and causes signal S to display its stop indication.

In addition, under these conditions, a circuit is not established for supplying energy from the battery 12 to the relay FSA and its contact 17 is certain to remain released.

If front contact 16 of relay TR fuses and remains closed, and if at the same time back contact 14 of relay TR fuses, the relay FSA will be short circuited over an obvious circuit and will remain released.

Likewise, if back contact 16 and front contact 14 of relay TR fuse and remain closed, the relay BSA will be short circuited over the circuit controlled by front contact 17 of relay FSA if relay FSA is picked up, but under these circumstances relay FSA will ordinarily be released because of the open front contact 16 of track relay TR. In any case relay BSA will be released and maintain the display of the stop indication by signal S.

Since bridging or overlapping contacts on the track relay TR cannot result in improper energization of the relay BSA, there is no possibility that the relay BSA will be picked up unless the relay TR is responding to coded energy. Accordingly, at times when the relay TR is not responding to coded energy, as for example, when the section is occupied or the supply of coded energy over the section rails is cut off for any other reason, or if steady energy is supplied to the track relay, the relay BSA is certain to remain released and maintain the display of the stop indication by signal S, and there is no possibility that the relay BSA will be improperly picked up to cause signal S to display its green indication.

The principle embodied in the equipment shown in Fig. 1 is also applicable to situations where two track relays are employed and there is decoding means governed jointly by these relays. One example of such a situation is at an intermediate signal location in single track stretches where traffic is operated in one direction at times and in the other direction at other times.

In Fig. 2 of the drawing there is shown a portion of the equipment at an intermediate signal location. In order to simplify the disclosure, only the equipment essential to the understanding of this invention has been illustrated and the remainder of the equipment may be arranged in any appropriate manner, as, for example, as shown in Fig. 1c or 1d of Letters Patent of the United States No. 2,344,573 issued March 21, 1944, to J. J. Van Horn, or in Fig. 1c of Letters Patent of the United States No. 2,344,333 issued March 14, 1944, to J. J. Van Horn.

As explained in the above-identified Van Horn patents, the equipment for the track stretch is controlled so that when the stretch is prepared for westbound traffic, that is, from right to left, coded energy is supplied to the left-hand end of section 5T, and when the stretch is prepared for eastbound traffic, that is, from left to right, coded energy is supplied to the right-hand end of sec-

tion 6T. The coded energy supplied to the rails of sections 5T and 6T is of 75 or 180 code frequency according as the section in advance is occupied or unoccupied. The equipment at the signal location includes means, not shown, effective when traffic is established in one direction or the other to supply energy of 75 or 180 code frequency to one or the other of the coding relays 5ECTM or 6WCTM and thus cause coded energy to be supplied to the rails of one or the other of the sections 5T or 6T.

The equipment is shown in the condition which it assumes when traffic is not established in either direction. At such times the relays are all released and red lamps of the wayside signals 5WS and 6ES are lighted.

The first track relay 6ETR has a first movable contact 21 and a second movable contact 22 which are connected by a first supply conductor 19. The second track relay 5WTR has a first movable contact 25 and a second movable contact 24 which are connected by a second supply conductor 26. The contacts of the track relays 6ETR and 5WTR are biased to a first or released position and are movable therefrom to a second or picked-up position.

When the stretch is prepared for eastbound traffic, the first track relay 6ETR is operated by coded energy supplied over the rails of section 6T, and the second relay 5WTR is deenergized so that its contacts remain released. When the contacts of relay 6ETR pick up, energy is supplied to the first auxiliary relay 6EFSA over the circuit which is traced from the second or positive terminal of the battery 20 over front contact 21 of relay 6ETR, the first supply conductor 19, front contact 22 of relay 6ETR, winding of relay 6EFSA, back contact 23 of relay 5WFSA, back contact 24 of relay 5WTR, the second supply conductor 26, and back contact 25 of relay 5WTR to the negative or second terminal of the battery 20. The energy supplied to the winding of relay 6EFSA picks up the relay contacts with the result that during the released periods of the contacts of relay 6ETR energy is supplied to relay BSA over the circuit which is traced from the positive terminal of the battery 20 through the winding of relay BSA, front contact 27 of relay 6EFSA, back contact 22 of relay 6ETR, wire 19, and back contact 21 of relay 6ETR to the negative terminal of the battery 20. Accordingly, the contacts of relay BSA pick up and its contact 30 connects the winding of code following relay TM in multiple with the winding of relay BSA so that, during the release periods of relay 6ETR, relay TM is energized from battery 20 over the circuit just traced for relay BSA and the contact of relay TM picks up.

During subsequent picked-up periods of the relay 6ETR, energy is supplied to relay 6EFSA over the circuit traced above, and the supply of energy to relays BSA and TM is interrupted and relay TM releases. The relays 6EFSA and BSA are of a type the contacts of which are slow to release so that they remain picked up during code following operation of the relays 6ETR and TM and contact 30 of relay BSA maintains the circuit of relay TM.

An asymmetric unit or rectifier is connected in series with the winding of relay TM and is poled to permit energy from the battery 20 to energize the relay TM but to prevent the supply to relay TM of the energy induced in the winding of relay BSA on interruption of the supply of energy to the relay winding. If this energy

were supplied to relay TM, it would hasten release of the relay contact and might objectionably reduce the length of the picked-up periods of this contact.

When relay BSA picks up, its contact 31 establishes the circuit governed by the contact of relay TM for supplying energy from a source of direct current, not shown, the terminals of which are designated B and C in the drawing, to the primary winding of the decoding transformer DT, from the secondary winding of which energy is supplied through a resonant rectifier unit 18ODU to relay D to pick up the contacts of relay D when and only when the relay TM is operated by energy of 180 code frequency.

When relays BSA and 6EFSA pick up, energy is supplied to the yellow lamp Y or to the green lamp G of signal 6ES according as contact 32 of relay D is released or picked up. In addition, when relay BSA picks up, energy is supplied over its contact 34 and back contact 35 of relay 5WFSA to the red lamp R of signal 5WS.

During occupancy of section 6T the relay 6ETR remains released and does not establish the circuit of relay 6EFSA so that it remains released and does not establish the circuit of relay BSA. Accordingly, relay BSA is released and interrupts the supply of energy to the decoding transformer DT and to the lamps Y and G of the signal 6ES, and establishes circuits to maintain the supply of energy to the red lamps R of signals 6ES and 5WS.

When section 6T is vacated, the relay 6ETR is operated by coded energy and relays 6EFSA and BSA are again picked up.

When the stretch is prepared for westbound traffic, the relay 5WTR is operated by coded energy supplied over the rails of section 5T so that during picked-up periods of the relay energy is supplied to relay 5WFSA over the circuit which is traced from the positive terminal of battery 20 over front contact 25 of relay 5WTR, wire 26, front contact 24 of relay 5WFSA, back contact 27 of relay 6EFSA, and back contacts 22 and 21 of relay 6ETR to the negative terminal of battery 20. During the released periods of the relay 5WTR energy is supplied to relay BSA over the circuit which is traced from the positive terminal of battery 20 through the winding of relay BSA, front contact 23 of relay 5WSA, and back contacts 24 and 25 of relay 5WTR to the negative terminal of the battery. Accordingly, contact 30 of relay BSA is picked up to connect relay TM in multiple with relay BSA while other contacts of relay BSA establish the circuits of the decoding transformer and of the lamps Y and G of the signal 5WS, and signal 5WS displays a yellow or a green indication depending on whether relay D is released or picked up, while signal 6ES displays its red indication.

When section 5T is occupied, the relay 5WTR remains released so that relays 5WFSA and BSA are released, and energy is supplied to the red lamps of the signals 6ES and 5WS.

The equipment shown in Fig. 2 is arranged so that overlapping of the contacts on either of the track relays 6ETR and 5WTR will not result in improper display of a permissive indication by either of the signals.

If movable contact 21 of relay 6ETR simultaneously engages its front and back points of contact, the battery 20 will be short circuited and energy will not be supplied therefrom to relay 6EFSA or to relay BSA and relay BSA is certain to remain released. Similarly, if movable contact

25 of relay 5WTR simultaneously engages its front and back points of contact, the battery 20 will be short circuited and relays 5WFSA, TM and BSA will remain released and signals 6ES and 5WS will both display their stop indications.

If movable contact 22 of relay 6ETR simultaneously engages its front and back points of contact, and if at the same time contact 21 engages its front point of contact, energy will be supplied to relay 6EFSA over the circuit which is traced from the positive terminal of the battery 20 over contacts 21 and 22 of relay 6ETR, winding of relay 6EFSA, back contact 23 of relay 5WFSA, and back contacts 24 and 25 of relay 5WTR to the negative terminal of the battery. The energy supplied to relay 6EFSA picks up its contacts so that its contact 27 interrupts the circuit of relay 5WFSA and insures that it remains released, while, when contact 27 of relay 6EFSA is picked up, the relay BSA is short circuited over the circuit which is traced from the right-hand terminal of the relay winding over front contact 21 of relay 6ETR, wire 19, back contact 22 of relay 6ETR, and front contact 27 of relay 6EFSA to the left-hand terminal of the winding of relay BSA. Accordingly, relay BSA remains released to cause signals 6ES and 5WS to both display stop indications and does not establish circuits to permit signal 6ES or 5WS to display a permissive indication.

If contact 22 of relay 6ETR simultaneously engages its front and its back points of contact, and if at the same time contact 21 engages its back point of contact, the relay 6EFSA will be shunted over the circuit which is traced from the left-hand terminal of the relay winding over back contact 23 of relay 5WFSA, back contacts 24 and 25 of relay 5WTR, back contact 21 of relay 6ETR, wire 19, and front contact 22 of relay 6ETR to the right-hand terminal of the winding of relay 6EFSA. As the relay 6EFSA is shunted, its contacts remain released and do not establish the circuit of relay BSA so that it remains released.

Similarly, if movable contact 24 of relay 5WTR simultaneously engages its front and back points of contact, the relay BSA will be short circuited if contacts 25 engages its front point of contact, and relay 5WFSA will be short circuited if contact 25 engages its back point of contact. In either case relay BSA remains released and maintains the circuits for the red lamps of signals 5WS and 6ES.

Although I have herein illustrated and described only two forms of code detecting means embodying my invention, it is understood that various changes and modifications may be made therein within the scope of the appended claims without departing from the spirit and scope of my invention.

Having thus described my invention, what I claim is:

1. In combination, a code following relay having two movable contacts actuated between a first and a second position substantially in synchronism, a source of current having a first and a second terminal, a first slow releasing auxiliary relay having one terminal of its winding connected to the first terminal of said source, a circuit including said code following relay contacts in series for connecting the other terminal of the winding of said first auxiliary relay to the second terminal of said source of current when said code following relay contacts are both in their second position, a second auxiliary relay having one terminal of its winding connected to the second

terminal of said source, circuit means including in series a front contact of said first auxiliary relay and said code following relay contacts for connecting the other terminal of the winding of said second auxiliary relay to the first terminal of said source when said code following relay contacts are both in their first position, and a control circuit governed by a contact of said second auxiliary relay.

2. In combination, a code following relay having a first and a second movable contact which are actuated between a first and a second position substantially in synchronism, a source of current having a first and a second terminal, the first contact of said code following relay being effective according as it is in its first or its second position to connect a supply conductor to the first or the second terminal of said source, the second contact of said code following relay being effective when in its first position provided the first contact of said code following relay is also in its first position to establish a circuit including said supply conductor for supplying energy from said source to a first slow releasing auxiliary relay, said second contact of said code following relay being effective when in its second position provided the first contact of said code following relay is also in its second position to establish a circuit including said supply conductor and a front contact of said first auxiliary relay for supplying energy from said source to a second auxiliary relay, and a control circuit governed by said second auxiliary relay.

3. In combination, a code following relay having a first and a second movable contact which are actuated between a first and a second position substantially in synchronism, a source of current having a first and a second terminal, the first contact of said code following relay being effective according as it is in its first or its second position to connect a supply conductor to the first or the second terminal of said source, a first slow releasing auxiliary relay having one terminal of its winding connected to the first terminal of said source, the second contact of said code following relay being effective when in its second position to connect said supply conductor to the other terminal of the winding of said first auxiliary relay, said second contact of said code following relay being effective when in its first position provided the contacts of said first auxiliary relay are picked up to connect said supply conductor to the second terminal of said source in series with the winding of a second auxiliary relay, and a control circuit governed by a contact of said second auxiliary relay.

4. In combination, a code following relay having a first and a second movable contact which are actuated between a first and a second position substantially in synchronism, a source of current having a first and a second terminal, the first contact of said code following relay being effective according as it is in its first or its second position to connect a supply conductor to the first or the second terminal of said source, the second contact of said code following relay being effective when in its second position to connect said supply conductor to the first terminal of said source in series with the winding of a first slow releasing auxiliary relay, said second contact of said code following relay being effective when in its first position provided the contacts of said first auxiliary relay are picked up to connect said supply conductor to the second terminal of said source in series with the winding

of a second auxiliary relay, and a control circuit governed by a contact of said second auxiliary relay.

5. In a coded signaling system, in combination, a first and a second code following relay each of which is provided with a first and a second movable contact which are biased to a first position, means for at times actuating the contacts of said first code following relay between their first and a second position and for at other times actuating the contacts of said second code following relay between their first and a second position, the first contact of the first code following relay being effective according as it is in its first or its second position to connect a first supply conductor to the first or the second terminal of a source of current, the first contact of the second code following relay being effective according as it is in its first or its second position to connect a second supply conductor to the first or the second terminal of said source of current, the second contact of said first code following relay being effective when in its second position to connect said first supply conductor to the first terminal of said source in series with the winding of a first slow releasing auxiliary relay provided the contacts of a second slow releasing auxiliary relay are released and the contacts of said second code following relay are in their first position, the second contact of said first code following relay being effective when in its first position to connect said first supply conductor to the second terminal of said source in series with the winding of a third auxiliary relay provided the contacts of said first auxiliary relay are picked up, the second contact of said second code following relay being effective when in its second position to connect said second supply conductor to the first terminal of said source in series with the winding of said second auxiliary relay provided the contacts of said first auxiliary relay are released and contacts of said first code following relay are in their first position, the second contact of said second code following relay being effective when in its first position to connect said second supply conductor to the second terminal of said source in series with the winding of said third auxiliary relay provided the contacts of said second auxiliary relay are picked up, a circuit governed by said first and third auxiliary

relays, and a circuit governed by said second and third auxiliary relays.

6. In a coded signaling system, in combination, a first and a second code following relay each of which is provided with a first and a second movable contact which are biased to a first position, means for at times actuating the contacts of said first code following relay between their first and a second position and for at other times actuating the contacts of said second code following relay between their first and a second position, the first contact of the first code following relay being effective according as it is in its first or its second position to connect a first supply conductor to the first or the second terminal of a source of current, the first contact of the second code following relay being effective according as it is in its first or its second position to connect a second supply conductor to the first or the second terminal of said source of current, the second contact of said first code following relay being effective when in its second position to connect said first supply conductor to the first terminal of said source in series with the winding of a first slow releasing auxiliary relay provided the contacts of a second slow releasing auxiliary relay are released, the second contact of said first code following relay being effective when in its first position to connect said first supply conductor to the second terminal of said source in series with the winding of a third auxiliary relay provided the contacts of said first auxiliary relay are picked up, the second contact of said second code following relay being effective when in its second position to connect said second supply conductor to the first terminal of said source in series with the winding of said second auxiliary relay provided the contacts of said first auxiliary relay are released, the second contact of said second code following relay being effective when in its first position to connect said second supply conductor to the second terminal of said source in series with the winding of said third auxiliary relay provided the contacts of said second auxiliary relay are picked up, a circuit governed by said first and third auxiliary relays, and a circuit governed by said second and third auxiliary relays.

FRANK H. NICHOLSON.
